SUNDIAL

Vernon L. Bedinger, Portland, Oreg., assignor of a fractional part interest to Andrew Brown Haddow, Gladstone, Oreg.

Filed Jan. 4, 1973, Ser. No. 321,023

Term of patent 14 years

Int. Cl. D10—03

U.S. Cl. D10—45

FIG. 1

FIG. 2

FIG. 3

FIG. 4

FIG. 5

FIG. 1 is a front perspective view of a sundial showing my new design;

FIG. 2 is a front elevational view thereof;

FIG. 3 is a top plan view thereof;

FIG. 4 is a rear elevational view thereof; and

FIG. 5 is a left side elevational view thereof, the right side being a mirror image thereof.

I claim:

The ornamental design for a sundial, as shown and described.
